UNITED STATES PATENT OFFICE.

ANTON VAN VEEN, OF HARTFORD, CONNECTICUT, ASSIGNOR TO THE FULLER BRUSH COMPANY, OF HARTFORD, CONNECTICUT, A CORPORATION OF CONNECTICUT.

WINDING MACHINE.

Application filed November 13, 1923. Serial No. 674,486.

My invention relates to the class of machines employed for depositing threads by a winding operation upon a support, and an object of the invention, among others, is the production of a machine of this class whereby the winding operations may be rapidly conducted in a particularly efficient manner.

One form of machine embodying my invention and in the construction and use of which the objects herein set out, as well as others, may be attained, is illustrated in the accompanying drawings, in which—

Figure 1 is a top view of a machine embodying my invention.

Figure 2 (Sheet II) is a view in front elevation of the same.

Figure 3 (Sheet III) is a view in end elevation.

Figure 4 is a detail view, scale enlarged, illustrating the construction of a flier and its support.

Figure 5 is a detail view, scale still further enlarged, in section through the fliers, their supports and the driving mechanism therefor.

Figure 6 (Sheet II) is a detail view in vertical section through a portion of the machine on a plane denoted by the dotted line 6—6 of Figure 1, the scale being the same as that of Figure 1.

Figure 7 (Sheet I) is a detail view, scale enlarged, illustrating the construction and operation of the mechanism for imparting reciprocating movement to the thread form supporting bars.

Figure 8 is a detail view illustrating the mechanism as winding the thread upon the thread forms when the winding starts at the base of said forms.

While this invention particularly contemplates the deposit of threads upon forms from which said formed masses are subsequently removed, yet it is to be understood that the invention is not confined to a machine in which the deposited threads are to be subsequently removed, as the invention in many of its forms will be found applicable to machines of various constructions whereby thread may be deposited upon a core or form irrespective of the fact as to whether such formed mass is or not subsequently removed from the support for such mass.

In the accompanying drawings the numeral 10 denotes the bed of the machine

that may be suitably supported as upon legs 55 11, these parts being constructed of any suitable material. In the preferred form of construction the bed is of box form comprising ends 12 and a front 13 rising from the bed, the back being open, as illustrated 60 in Figure 1. A driving shaft 14 is supported in a bearing 15 at the upper end of a bracket 16 rising from the bed and is driven as by means of a belt passing around a pulley 17. A bevel gear 18 is mounted to rotate 65 on the shaft 14 and meshes with a bevel gear 19 rotatably supported at the upper end of a bracket 20 rising from the bed 10, the gear 19 meshing with a bevel gear 21 secured to a connecting shaft 9 rotatably mounted in 70 the front 13 and having a thread-form reciprocating pinion 22 secured thereto, one end of the shaft 14 being mounted in the bevel gear 21, but for rotation independently thereof. A clutch member 23 is splined to 75 the driving shaft 14 and has clutch pins arranged to engage clutch pins on the gears 18 and 21, in the position of the parts shown in Figure 1 the clutch member 23 being engaged with the gear 21, and the mechanism 80 being under operation to wind thread as shown. A clutch lever 24 is pivotally supported on a post 25 rising from the bed 10, this lever being forked and having pins engaging within a groove in the clutch member 23 in a manner that will be readily understood.

A clutch actuating lever 26 is pivotally supported on the bed, as shown in Figure 6 of the drawings, one end of this lever being 90 pivotally attached to the clutch lever 24 and its opposite end being pivotally attached to a clutch actuating rod 27 slidably mounted in the front 13 and in a bracket 28 secured to one of the ends 12, said rod being in two sections united by a connector 50 adjustably secured to each section, as shown in Figures 1, 2, and 3 and having a clutch actuating knob 29 secured to its outer end, as shown in Figure 1 of the drawings.

A flier driving gear 30 is secured to the connecting shaft 9 and meshes with one of a train of flier gears 31 rotatably supported by the front 13 and successively meshing one with another as shown in Figures 1 and 2, said gears being mounted upon hollow studs extending through said front and forming thread guides 32. Fliers are secured, one to

each of the gears 31, said fliers each having thread guides 34 projecting therefrom to receive threads 35 extending from spools or bobbins 36 rotatably mounted on supports rising from the bottoms of thread boxes 37 located underneath the machine frame, said threads passing through the thread guides 32 in the front 13 and through the guides 34 on the fliers 33, as shown in Figure 1.

A thread-form reciprocating pinion 38 is secured to rotate with a flier gear 39 at that end of the train of flier gears opposite to the gear 30, and each of the pinions 22 and 38 meshes with a thread guide reciprocating gear 40, each of which gears is secured to a thread-form reciprocating shaft 41 rotatably mounted in the front 13 and in a bracket 28, there being one of these brackets secured to an end 12 at each end of the machine. Each of said reciprocating shafts is threaded (in opposite directions in the structure shown herein) to engage a threaded hole in a traveler 42, said travelers each supporting one end of a thread-form supporting bar 43 extending across the machine from end to end, and as shown in Figure 1 of the drawings.

Thread-forms 44 are secured to and extend from the bar 43, these forms being arranged in sets, each set being secured to the opposite side of said bar from the other set, and the members of each set projecting outwardly away from the bar. Each of these thread-forms is forked and each of said forms has thread receiving notches 45 at its base and thread receiving notches 46 at its end, these notches being shaped to pinch the thread and serving as a means of attachment of the end of a thread when it is first secured to a thread-form. The travelers are guided in their movements by a guide engaging each of them, these guides being in the form of rods, one of which guide rods 47 is located at one end of the machine, and the clutch actuating rod 27 serving as the other guide, both of which pass through the travelers 42 to guide it and prevent cramping action thereof.

Stop collars 48-49 are secured to the rod 27 on opposite sides of the part of the traveler engaging said rod, these collars being spaced a proper distance apart to effect a stopping operation at the proper time.

The operation of the machine is as follows:

To start the operation of the machine the threads 35 are each extended through the guides 32 in the ends 13 and through the guides 34 on the fliers 33 and the end of each thread is then engaged with a notch at the outer end or at the base of a thread-form, depending upon the position of the thread-forms with respect to the fliers. If the fliers are in the positions as shown in Figure 1, the threads will be engaged with

the notches at the outer ends of the thread-forms, and as the bar 43 is moved inwardly or toward the front 13 the winding will take place from the end of the form to the base. If the thread-forms are located at the inner ends of their paths of movement, that is with the bar 43 nearest the front 13, as shown in Figure 8, the threads will be engaged with the notches at the bases of the thread-forms.

Assuming that the bar 43, at the beginning of the operation, is substantially in the position shown in Figure 1, and that no thread has been wound upon either of the sets of thread-forms, and that the threads are engaged with the notches at the outer ends of said forms, and that the machine has been set in operation and that the winding has just begun, the fliers operating as shown in Figure 1, will sweep around the thread-forms in opposite directions, that at the right rotating in a clockwise direction, when looking from the front of the machine, and the thread guide reciprocating shafts 41 will be rotated in a direction to cause the thread-forms 44 between the bar 43 and the front 13 to travel toward said front. In this operation the clutch member 23 is engaged with the clutch member on the gear 21, which parts are driven by the shaft 14 and the pulley 17, power being applied through the clutch member 23 and gear 21 to the connecting shaft 9 and by the latter to the intermeshing gear 30, &c., the gears 18 and 19 rotating idly. This describes the beginning of a winding operation and not a continued operation shown as taking place in Figure 1. If, at the beginning of the operation, the thread-form supporting bar 43 should be at the opposite end of its path of movement from that shown in Figure 1 the threads would be engaged with the notches 45 at the bases of the thread-forms, from which the winding operation would start, as shown in Figure 8, this figure, however, showing the parts as operated in a continued winding operation and not at the beginning of a winding operation.

Let it now be assumed that a continued winding operation is taking place, this after the thread has been wound upon the forms shown at the opposite and front side of the bar 43. In this operation the parts will be rotating as above described. As the bar 43 approaches the end of its path of movement nearest to the front 13 the stop 48 will be engaged by the traveler 42 at the right hand end of the machine, the rod 27 will be pushed inwardly and as a consequence the clutch member 23 will be disengaged from the gear 21 and the operation of the machine will cease, this taking place when the thread has been wound along the forms to the bases of each of said forms.

During this operation the operative cuts

the threads that pass from the thread-forms at the front of the bar 43 to the thread-forms on the back of said bar, and on which the thread is being wound, inserts one of the 5 branches of a U-shaped holder 51 through the opening between the forks of each thread-form so that the legs of each holder will be on opposite sides of the thread-form, and places a ring 52 over said legs to hold 10 them together and thus clamp the wound thread mass securely to retain it in shape for a subsequent operation, which operation comprises the placing of two wires on opposite sides of a thread mass, the removal of 15 the holder, and the twisting of said wires to secure the thread mass, and thus form a mop. This twisting operation, however comprises no part of the present invention. When the holders have been secured as above 20 set out the thread masses are removed from the thread forms.

After the machine has been stopped, as above described, and the wound masses have been removed from the forms extending 25 from the front of the bar 43, as above described, the operative rotates the thread bar to locate the thread-forms at the front and the forms from which the thread masses have been removed at the back of the bar 30 43, the threads now extending from the outer guide 34 on each of the fliers straight to a wound thread mass on a form at the front of the bar 43. The knob 29 is now pulled 35 out, it having, in the previous winding operation been pushed in, and the clutch members are engaged as shown in Figure 1, and the winding operation starts as shown in said figure. As this winding operation starts 40 the threads are passed to the opposite sides of the wound thread masses at the front of the bar 43, across said bar and around the thread-forms on which the winding is to take place, as shown in Figure 1, after which the operation proceeds as above described.

45 In the mechanism as herein illustrated each of the thread-forms consists of two members, one 53 of which is pivotally mounted in the bar 43, such pivoted member in fact comprising the pivoted member of two 50 thread-forms located on opposite sides of said bar, that is said member projects through the bar the other member 54 of each thread-form also projecting through and being rigidly secured to the bar 43. A thread-form expanding and contracting bar 55 is pivotally attached to each of the pivoted thread-form members above described, as shown in Figure 1, this bar 55 having a pin 56 engaged in a cam slot in a disc 57 secured to a thread-form expanding and contracting shaft 58 rotatably mounted in the bar 43 and having a thread-form expanding and contracting wheel 59 secured to each end by means of which the thread-forms may 60 be expanded or contracted as occasion may 65

demand. In the winding of some threads it becomes necessary to contract the thread-forms in order that the wound masses may be readily removed, and the mechanism described affords ready means for doing this, 70 just before the thread masses are removed, and for again expanding said forms preparatory to receiving wound masses of thread thereon, the wheels 59 being located at each end of the shaft 58 so that one will be always located in front of the bar 43 and readily accessible for the purpose specified. 75

The bar 43 is provided with means for frictionally retaining it in different winding positions, this means comprising a collar 60 80 secured to said bar and having recesses to receive spring pressed detents 61 located in sockets in one of the travelers 42, and as shown in Figure 7 of the drawings.

The fliers 33 are each adjustably mounted, 85 being secured to a flier base 62, the latter being adjustably secured upon a hub of one of the gears, 31 or 39.

In accordance with the provisions of the patent statutes I have described the principles 90 of operation of my invention, together with the device which I now consider to represent the best embodiment thereof; but I desire to have it understood that the device shown is only illustrative and that the invention may be 95 carried out by other means and applied to uses other than those above set out.

I claim—

1. A winding machine including a thread-form supporting bar pivotally mounted to 100 locate thread-forms in winding positions, thread-forms projecting radially in opposite directions from said bar, each of said forms including a member projecting through and in opposite directions from said bar and 105 comprising a portion of two thread-forms, and means for effecting the winding of thread upon said forms upon both sides of said bar.

2. A winding machine including a thread-form supporting bar pivotally mounted to 110 locate thread-forms in winding positions, thread-forms projecting radially in opposite directions from said bar, each of said forms including a fixed member and a member pivotally attached to and extending through and in opposite directions from said bar and 115 comprising a portion of two thread-forms, said pivoted member being movable with respect to said fixed member, and means for 120 effecting the winding of thread upon said forms upon both sides of said bar.

3. A winding machine including a thread-form supporting bar pivotally mounted to 125 locate thread-forms in winding positions, thread-forms projecting radially through and in opposite directions from said bar, each of said forms including a plurality of members projecting in opposite directions from said bar, each of said members com-

prising a portion of two thread-forms, and means for effecting the winding of thread upon said forms upon opposite sides of said bar.

5 4. A winding machine including a thread-form supporting bar pivotally mounted to locate thread-forms in winding positions, thread-forms projecting radially in opposite directions from said bar, each of said forms including a fixed member and a member pivotally attached to and projecting in opposite directions from said bar and movable with respect to said fixed member, means for swinging said member on its pivot, and 10 means for effecting the winding of thread upon said forms upon both sides of said bar.

5 5. A winding machine including a thread-form supporting bar pivotally mounted to locate thread-forms in winding positions, a plurality of sets of thread-forms, each set comprising a plurality of thread-forms projecting radially in different directions from said bar, each of said sets including a fixed member and a pivotally mounted member comprising a portion of two thread forms, said pivoted member being movable with respect to said fixed member, a device for swinging all of said pivotally mounted members on their pivots, and means for effecting the winding of thread upon said forms upon opposite sides of said bar.

20 6. A winding machine including a pivotally mounted thread-form supporting bar, thread-forms projecting radially in opposite directions and substantially in line from said bar, a device located substantially in line with said forms for delivering thread from one to the other of said forms for a winding operation thereon and means for effecting a relative movement in opposite directions between said bar and said device and lengthwise of said forms to wind thread along said forms.

25 7. A winding machine including a thread-form supporting bar, a thread-form projecting therefrom, a device for delivering thread to said form for a winding operation thereon, a threaded shaft operatively connected with said bar, and driving mechanism including means for rotating said threaded shaft in opposite directions for passing thread in opposite directions along said forms.

55 8. A winding machine including a pivotally mounted thread-form supporting bar, thread-forms projecting radially in opposite

directions from said bar, a device for delivering thread to said forms for a winding operation thereon, a threaded shaft operatively connected with said bar, and driving mechanism including means for rotating said threaded shaft in opposite directions for passing thread along said forms.

9. A winding machine including a thread-form supporting bar pivotally mounted to locate thread forms on opposite sides thereof in winding positions, thread forms projecting radially in opposite directions from said bar, a row of intermeshing gears, means for imparting rotation to the gear at one end of said row, means at the other end of said row for imparting traversing movement to said bar, and a flier secured to each of said gears to wind thread about said thread forms.

10. A winding machine including a pivotally mounted thread form supporting bar, thread forms projecting in opposite directions from said bar, means for moving said bar in one direction to wind thread upon the thread forms upon one side thereof, means for moving said bar in opposite directions to wind the thread upon the forms upon the opposite side thereof, and means for winding thread about said thread forms.

11. A winding machine including a thread form supporting bar, thread forms projecting from one side of said bar and each comprising two members relatively movable one with respect to the other and upon which the thread is wound, and means for delivering thread to each of said forms.

12. A winding machine including a pivotally mounted thread form supporting bar, thread forms projecting radially in opposite directions from said bar, each of said forms comprising two members relatively movable one with respect to the other, and means for effecting the winding of thread upon said forms.

13. A winding machine including a thread form supporting bar pivotally mounted to locate thread forms in winding positions, thread forms projecting radially in different directions from said bar, each of said forms comprising two members relatively movable one with respect to the other, and a device for delivering thread separately to all of said thread forms for the winding operation thereon.

ANTON VAN VEEN.
